GUSTAF GRÖNDAL, OF DJURSHOLM, AND LORENS CARLSON, OF STOCKHOLM, SWEDEN.

TUNNEL OVEN.

Application filed November 6, 1924. Serial No. 748,193.

It has been found, that shales, schists and other comparatively very bituminous materials may very easily be distilled by heating, probably for the reason that the bitumen primarily is transformed into a semi-fluid mass, which by destructive distillation generates gas from which oils are obtained by means of condensation. For that reason such a material cannot be treated in the distilling apparatus (Scottish retorts or revolving drums) hitherto used, because the material during the heating will stick to the walls of the apparatus and thereby cause interruptions in the process.

Our invention relates to a process and an apparatus suitable for the rational treatment of such coking materials.

According to the invention the material in the shape of powder, small pieces or bricks is placed in thin layers upon a bed (for instance trays or shelyes), which is subjected to an indirect heating in a closed chamber by means of combustion gases, passing through heating means (radiators, fire channels or the like) in the chamber and at this passage emitting heat to the material, directly by radiation as well as indirectly by means of the gases and vapors, generated during the process and indirectly also by steam introduced into the chamber. The material hereby is decomposed, and expels oil vapors and gases, which are collected and condensed in the usual manner. When the treatment of the material is finished the supporting trays and the remainders upon them are removed from the heating chamber and the remainders removed from the supporting trays, which afterwards are charged with fresh material and again introduced in the said chamber.

The heating operation preferably may be carried out in several steps of different temperatures, for which purpose the trays may be placed on cars, which are continuously or intermittently moved through an elongated heating chamber, the different parts of which are heated to different temperatures, whereby the process is accelerated and the production thus increased. In place of moving the material through the heating chamber the combustion (heating) gases may be introduced successively in different parts of the said chamber; in this case the chamber with its heating means may be arranged, for example, as a Hoffman ring

kiln, and the material with its supporting trays be stationary.

The trays are piled up with interspaces on the cars, the one upon the other, for facilitating the access of the heat to the material.

For facilitating the transmission of the heat to the material gas circulating means, as fans, are suitably arranged in the heating chamber.

After the passage through the said chamber the supporting trays with the remainders upon them are suitably cooled with water, and the steam thereby generated introduced into the heating chamber, whereby heat, that otherwise would be lost, can be utilized.

In the accompanying drawing a constructional form of a tunnel oven suitable for the process now described is illustrated in a vertical longitudinal section in Fig. 1 and in a horizontal longitudinal section in Fig. 2; Figs. 3, 4 and 5 illustrate respectively vertical cross sections along the lines III—III, IV—IV and V—V (Fig. 2).

The funnel oven contains an elongated chamber A, which at its ends is provided with closing means, a fore chamber B at the one and a cooling chamber C at the other end. At either side of the chamber sets of heating elements d, e, i, are arranged, heated by means of combustion gases from fire places f, g situated outside the tunnel oven, so that the material upon the cars introduced from the fore chamber B is at first submitted to a drying on the stretch $x-x_1$ by means of the comparatively weakly heated elements i, thereafter to a rapid heating to about 400° C. on the stretch x_1-y (by means of the more highly heated elements d), thereafter to a more feeble heating on the stretch $y-y_1$ (where the elements have a lower temperature) and finally to a somewhat higher temperature on the stretch y_1-z for expelling the last remainders of the oil. The temperature of the elements on the stretch $y-y_1$ may, as stated, be lower than that on the stretch x_1-y , because the material on the stretch last mentioned has already been heated to such a high temperature, that the distillation of the material on that stretch is already in full action and runs exothermically without any further supply of heat.

The combustion gases from the furnace g are introduced into the set of elements e at

the end nearest the cooling chamber, pass through the set to the adjacent end of the set *d*, where they meet the combustion gases from the fire place *f*, which gases have passed through the set of elements *d* in a direction opposite to that of gases first mentioned. The two currents of gases pass together through channels *h* under the set of elements *d* and enter into the set of elements *i*, through which they flow to the chimney *k*.

The parts of the elements *d* and *e*, which are situated nearest to the fire places of course obtain the highest temperature, while the elements *i* have the lowest one.

In the heating chamber ventilators (circulation fans) *l* are arranged for increasing the circulation of the gases and localizing the temperature in the chamber within narrow limits, for which purpose they are situated on determined places of the chamber. The steam expelled from the material on the stretch *x*—*x*₁ is brought into circulation in this part of the chamber by means of the ventilators placed nearest the inlet, but when more such steam is expelled it flows over to the stretch *x*₁—*y*, where it is heated to a relatively high temperature by the elements *d* and is brought into circulation about the material on this stretch. This material hereby is heated to 350°—400° C., whereby very much oil is expelled, an expelling that continues exothermically on the stretch *y*—*y*₁ where for that reason any transmitting of heat is not quite necessary and the use of ventilators thus not required. Near to the outlet end of the heating chamber such ventilators *l* are placed for producing a brisk circulation on the stretch *y*₁—*z*, thereby transmitting the heat from the strongly heated elements *e* to the material and removing the last remainder of the oil therefrom.

Conduits *m* open into the cooling chamber *C* for the introduction of cooling water to the hot cars with their charge whereby steam is generated and also other tubes *n* for carrying such steam to the stretch *y*₁—*z*, (or *x*₁—*y*) in the heating chamber *A*. Chamber *A* is also provided with conduits *o* for carrying the disengaged oleiferous gases to a condensing device not illustrated on the drawing.

In the treatment of highly bituminous shales, etc., the remainders after the distillation may be coked to such an extent that they stick to the supporting beds; for avoiding this inconvenience the trays before their charging may be powdered with a thin layer of the pulverized remainder or any other suitable material.

The process (as well as the funnel oven) of course may also be used for noncoking material and affords in both cases the advantage of permitting a working up of the material in a powdered form.

Having now particularly described the nature of our invention and the manner of its operation, what we claim is:

1. A tunnel oven for distilling oil and other products from bituminous materials as shales, schists, coal and the like, comprising movable cars, trays piled up with interspaces upon such cars and carrying the material thereon in thin layers, heating devices situated inside the oven, means for closing the oven at its inlet and outlet ends, outlets for the vapors and gases generated in the distillation, and fans arranged in the distillation chamber itself for producing a circulation of the said vapors and gases. 86

2. A tunnel oven for distilling oil and other products from bituminous materials as shales, schists, coal and the like, comprising movable cars, trays piled up with interspaces upon such cars and carrying the material thereon in thin layers, heating devices situated inside the oven, means for closing the oven at its inlet and outlet ends, outlets in the oven for the vapors and gases generated in the distillation, fans arranged in the distillation chamber for circulation of the vapors and gases, a cooling chamber at the outlet end of the oven, conduits for introducing water into said chamber to cool the material introduced therein, and other conduits for conducting the steam generated in the cooling chamber to the distillation chamber. 90

3. A tunnel oven for distilling oil and other products from bituminous materials as shales, schists, coal and the like, comprising movable cars, trays piled up with interspaces upon such cars and carrying the material thereon in thin layers, means for closing the oven at its inlet and outlet ends, outlets in the oven for the vapors and gases generated in the distillation, circulation fans in the distillation chamber, heating devices situated inside the oven and consisting of three sets of heating flues arranged in succession lengthwise of the oven, an outer furnace for each of the two sets of heating flues nearest the outlet end of the distillation chamber and arranged to supply heating gases to said flues, a common flue communicating with the said two sets of flues and opening into the set nearest to the inlet end of the distillation chamber. 100

4. A tunnel oven for distilling oil and other products from bituminous materials as shales, schists, coal and the like, comprising movable cars, trays piled up with interspaces upon such cars and carrying the material thereon in thin layers, means for closing the oven at its inlet and outlet ends, outlets for the vapors and gases generated in the distillation, fans arranged in the distillation chamber for circulation of the vapors and gases, a cooling chamber at the outlet end of the oven, conduits for intro- 115

ducing water into said chamber to cool the material introduced therein, and other conduits for conducting the steam generated in the cooling chamber to the distillation chamber, heating devices situated inside the oven and consisting of three sets of heating flues arranged in succession lengthwise of the oven, an outer furnace for each of the two sets of heating flues nearest the outlet end of the distillation chamber and ar-

ranged to supply heating gases to said flues, a common flue communicating with the said two sets of flues and opening into the set nearest to the inlet end of the distillation chamber.
